UNITED STATES PATENT OFFICE

SIDNEY ROSENTHAL, OF CEDARHURST, NEW YORK, ASSIGNOR TO B. BLUMENTHAL & CO. INC., OF NEW YORK, N. Y.

DESIGN FOR A BUCKLE

Application filed December 19, 1932. Serial No. 46,526. Term of patent 3½ years.

To all whom it may concern:

Be it known that I, SIDNEY ROSENTHAL, a citizen of the United States, residing at Cedarhurst, L. I., in the county of Nassau and State of New York, have invented a new, original, and ornamental Design for a buckle, of which the following is a specification, reference being had to the accompanying drawing, forming part thereof.

Fig. 1 is a plan view of a buckle, showing my new design.

Fig. 2 is a side view thereof.

I claim:

The ornamental design for a buckle, as shown.

SIDNEY ROSENTHAL.
